UNITED STATES PATENT OFFICE.

RICHARD T. PEARCE, OF COVINGTON, KENTUCKY.

SPLICE FOR WICK ENDS AND THE LIKE.

Application filed April 7, 1926. Serial No. 100,408.

This invention relates to a combustible splicing element for joining together two ends of braided or twisted candle wicking and has for an object the provision of such 5 splices or joints as will permit of the economical use of candle wicking in candle making machines.

Another object is to provide a method for splicing candle wicking which may be employed both by the maker of said wick and also by the candle maker to the end that both manufacturers are enabled to avoid waste of manufactured wicking and thus effect a considerable saving in money.

15 Another object is to provide a splice for wicking which is combustible and which may therefore be positioned within the body of a candle without any derogatory effect upon the burning thereof.

20 Another object is to provide a means and method for the purposes stated which may be employed and practiced by operators of candle making machinery whereby a considerable amount of time and labor is saved 25 during the process of candle making.

Another object is to provide a means and method for the purposes stated which will enable a manufacturer to assemble odds and ends of his manufactured stock in such a 30 way as to be accepted by the trade on a par with whole units of said stock. These and other objects are attained by the means and method described herein and disclosed in the accompanying drawing, in which:

35 Fig. 1, is a cross sectional view of a machine candle mold having extending therethrough a section of wicking spliced by the means and method of my invention.

40 Fig. 2, is a perspective view of a steel sleeve forming a part of a piston through which the wicking passes.

Fig. 3, is a perspective view of a splicing element of my invention prior to its application to wicking.

45 Fig. 4, is a view showing two pieces of wicking joined by a splice of my invention and wherein the splice is considerably less in diameter than the wicking.

50 Fig. 5, is a similar view showing a splice of substantially the same diameter as the wicking.

Fig. 6, is a cross sectional view on line 6—6 of Fig. 4.

55 Fig. 7, is a longitudinal cross section of a splice formed by the means and method of my invention.

The splicing means and method of my invention will be explained as relates to its use both by the manufacturer of candle wicking and by the manufacturer of both hand and machine made candles.

In the manufacture of candle wicking, the manufacturer markets his product to best advantage by providing spools of wicking containing a given number of feet, for example, 300 feet. In the manufacture of this wicking a number of threads of wicking material are twisted together to form a single strand and a number of these strands, for example three or six are twisted or braided together to form a continuous length of wicking. When in the manufacture of wicking any of the individual spools of soft thread become exhausted while other relatively full spools are still in the twisting or 65 braiding machine a new spool is inserted and the end thereof is grouped with the other threads comprising a given strand and the machine continues to produce an unbroken 70 length of wicking regardless of the occasional splicing in the threads of the strands or in the strands of the wicking.

It follows from this practice, however, that the length of wicking turned out by the loom or braiding machine will not be uniform and that the manufacturer often finds the length of wicking upon the various spools to vary from a few feet to a hundred feet or more. This market, however, because of the requirements of candle making machinery 80 demands a practically uniform length of wicking per spool. This demand is occasioned by the fact that a single machine may have a capacity for making as many as five hundred candles simultaneously and therefore would require an equal number of spools of wicking and that when one or more spools 85 become exhausted it is necessary to stop the machine and replenish the wicking. In order to eliminate as many stops as possible 90 the candle manufacturer demands uniform length of wicking. The manufacturer therefore winds the wicking upon spools in uniform lengths, for example, 300 feet, and after the output of a given loom has exceeded this 95 amount by any number of feet less than a unit, he cannot find a market for the remaining part of his manufactured product, but must again treat it as raw stock for the manufacture of the threads. By the present 100 described means and method the manufacturer of wicking is enabled to join together 105

110

the odd lengths of wicking in order to provide spools containing the standard length which are then acceptable to the candle manufacturer. In the manufacture of machine 5 made candles a large number of pistons such as 10, see Fig. 1, are employed. A single machine may have from three to five hundred of said pistons each having a steel sleeve or bushing 11 through which candle wicking 10 is threaded and extends through the cylinder mold 13. Inasmuch as it requires considerable time to thread an end of a spool of wicking through each of the numerous pistons 10 and sleeves 11, a great saving in 15 time and labor can be had by employing the simple and rapid splicing of my invention. In other words by employing a splice which is less than the diameter of the wicking and one which will have no derogatory effect 20 upon the burning of the finished produce, it is possible to take the end of the wicking on a depleted spool, then splice the end of the wicking on a wick of a new spool in less time than would be required to thread a new 25 wick through the piston and sleeve. After the finished candles are discharged new lengths of wicking are unrolled from the spool and are drawn through the sleeve 11. For this reason it is essential that the splice 30 be at least of the same diameter or less than the diameter of the wicking.

The means for splicing together ends of candle wicking and the like consists of a sheet or strip of celluloid or other combustible material 14 of about $\frac{3}{16}$ to $\frac{1}{2}$ inch in width which may be passed about the two unfrayed abutting ends of wicking to form a collar for holding the ends together. The combustible material 14 employed is preferably of a specially prepared celluloid in order to attain the best results, however, any combustible material which is adaptable to be tightly clamped about the ends may be satisfactorily employed. The length of the strip is such that when formed into a collar the outside diameter of said collar will be equal to or smaller than the normal diameter of the wicking. When the wicking to be spliced is for use in candle making machines, 45 it is essential that the diameter of the splice be not greater than the diameter of the wicking, in order that the spliced portion will pass through the steel sleeve 11 in the piston 50 of the candle mold.

In order to splice together two unfrayed ends of wicking 12, a piece of celluloid such as 14 is treated with a softening fluid and then passed about the wicking at the place where the ends abut, whereupon the parts 55 are placed between a pair of suitable steel dies which are then placed together and electrically heated for compressing the whole to a diameter substantially less than the normal diameter of wicking. When the heat 60 and pressure are removed the celluloid 14

immediately hardens upon being subjected to normal atmospheric temperature and it retains its shape holding the two ends of wicking compressed and retaining them against separation. 70

The splice thus formed being of somewhat lesser diameter than the wicking will pass smoothly through the steel sleeve 11 of the candle mold. The splicing operation may be easily and rapidly performed and 75 presents a perfect splice so that the wicking may be used for either hand or machine made candles. This makes the herein described splice very desirable over the formerly used method of fraying the ends of 80 wicking to be joined and then sewing them together by hand.

The advantageous manner in which the manufacturer of candle wicking may employ the means and method of splicing on 85 my invention has been previously described. The user of candle making machinery often finds that although he has secured spools containing substantially uniform lengths of wicking, or at least spools containing not 90 less than a given minimum, the wicking may stretch somewhat more in some molds than in others wherefore the series of spools on a given machine will not become simultaneously depleted. The end of a new spool of 95 wicking may be rapidly and conveniently spliced to the last end of a depleted unit and the new spool replaced with the empty one so that it is not necessary for the operator to again thread the wicking through the piston 10 and sleeve 11. This enables the operator of candle making machines to effect a great saving in time and labor. It has been found that by initially loading 100 the candle making machine with spools or bobbins containing substantially uniform lengths of wicking that when the first supply of wicking has been practically exhausted, the remaining lengths upon the various spools or bobbins may vary a few 105 feet in length. These remaining portions of wicking are then removed from the bobbins and the ends thereof spliced by the means and method of my invention to new 110 spools or bobbins and the varying excess amounts reeled onto new spools or bobbins which are then mounted on the machine. By following this procedure there is occasioned no waste of wicking and in addition thereto a great saving of time is effected, because the necessity for threading 115 the wicking through the many pistons is eliminated.

What I claim is:

1. The method of splicing together two unfrayed ends of candle wicking, comprising placing the said two ends of wicking in abutment, passing a split collar of combustible material about said ends, simultaneously molding the collar and compressing 130

the wicking to a diameter substantially less than the normal diameter of the wicking.

2. The method of splicing together two ends of candle wicking for forming a combustible splice comprising placing the two ends of candle wicking in abutment, passing a thin sheet of combustible material about the abutting ends of wicking whereby to encase the wicking for a distance on each side of the place of abutment, positioning the parts in a mold and subjecting them to heat and pressure to reduce the diameter of the assembled parts to substantially less than the normal diameter of wicking and to form the combustible material into intimate engagement with the wicking, then permitting the combustible material to cool, removing the parts thus treated from the mold whereupon the combustible material become hardened and retains the compressed

ends of wicking in abutment and against separation.

3. A candle wick comprising a pair of wick sections having abutting ends and a combustible sleeve receiving the abutting ends and compressing said ends, whereby the sleeve and ends attain a combined thickness not in excess of the normal diameter of the noncompressed wick sections. 25

4. A candle wick comprising a pair of wick sections having abutting ends and combustible means surrounding and compressing said ends for holding them together and providing a joint of a diameter not in excess of the normal diameter of the noncompressed wick sections. 30 35

In testimony whereof, I have hereunto subscribed my name this 6th day of April, 1926.

RICHARD T. PEARCE.
